UNITED STATES PATENT OFFICE.

HARRY CUMPSTY PROCTER, OF MANCHESTER, ENGLAND.

ELECTRIC LIGHTING APPARATUS FOR MOTOR VEHICLES.

Application filed September 16, 1926, Serial No. 135,905, and in Great Britain May 26, 1925.

This invention relates to that kind of electric lighting apparatus for motor vehicles wherein a detector lamp bulb is provided on the dash board or other place visible to the driver and is in an electric circuit controlled by electro-magnetic means provided in the rear or other light circuit and adapted to interrupt the first named circuit until deenergized by breakage of the rear or other light circuit for example by failure of the rear or other light bulb.

The main object of my invention is to provide an improved construction of apparatus.

I attain this object by the apparatus hereinafter described and claimed and for the purpose of description I refer to the accompanying drawing, in which—

Figure 1 is a front view of an apparatus in accordance with my invention.

Figure 2 is a front view thereof with the cover removed.

Figure 3 is a side view thereof with the cover removed.

Figure 4 is a rear view thereof.

Figure 5 is a diagrammatic view of an electric lighting circuit for the rear light, the said circuit embodying the said apparatus.

Referring to Figures 1 to 4 of the drawings, the apparatus shown therein comprises a base 1 of insulating material having a projecting member 2 of insulating material provided on it. A lamp holder 3 having a

metal base piece 4 is mounted on the member 2 to receive the detector lamp, the holder 3 being adapted to receive an exactly similar lamp to that employed in the rear lamp holder 34, Figure 5. An electro-

magnet consisting of wire coils 8, Figure 5, wound on a bobbin 5 having a core 6 is attached to the base 1 by means of a strap 7, and a spring 9 is attached at one end to a metal post 10 provided on the base

piece 4. The other end of the spring 9 is provided with an armature 11 adapted to be acted on by the electro-magnet and an electric contact screw 12 is mounted on a bracket 13 which is attached to the base 1, the screw 12 being arranged for the armature 11 to make contact with under the action of the spring 9 when the electro-

magnet is deenergized. A terminal 14 provided at the rear of the base 1 is electrically connected to the bracket 13. There are also three terminals 15, 16 and 17 provided at

the rear of the base 1, the terminal 15 being connected by a wire 18 to the terminal 14, the terminal 16 by a wire 19 to one end of the coil 8 and by a wire 20 to the plunger 21 of the lamp holder 3, and the terminal 17 by a wire 22 to the other end of the coil. The plunger 23 of the lamp holder 3 is connected by a wire 24 to the metal base piece 4 and thereby through the spring 9 to the armature 11.

A cover 36 has an aperture 25 for inserting and observing a lamp bulb in the holder 3 and removing the said lamp bulb from the holder 3. Where the apparatus is intended to be applied to the dash board of a motor vehicle, a flange 26 may be provided on the cover 36 for convenient attachment. Sunk lugs 27 are provided in the cover 36 for attachment thereof to the base 1 by means of screws 28.

Figure 5 illustrates the method of connecting the apparatus to the electric lighting switch and the rear lamp, those electrical connections existing in the apparatus being shown in full lines and the external connections being shown in broken lines.

The main, two-pole lighting switch 29 connected to the accumulator 30 of the vehicle is also connected by a lead 31 to the terminal 15 and by a lead 32 to the terminal 16. The feed wire 33 to the lamp holder 34 of the usual rear lamp is connected to the terminal 17 and the return 35 is connected to the terminal 14.

In use the spring 9 normally completes the circuit for the detector lamp inserted in the holder 3 but immediately any current passes through the rear lamp inserted in the holder 34, the electro-magnet is energized and the armature 11 attracted to it thereby breaking the circuit for the detector lamp. Should the rear lamp fail, the armature 11 is immediately released and the circuit to the detector lamp is completed, which lamp then lights up. The detector lamp constitutes a spare which may at any time be used to replace the rear lamp should another not be available at the time, and another lamp be subsequently obtained to replace the detector lamp. The apparatus thus serves the dual purpose of a detector and a spare bulb carrier.

The detector lamp is only in use in the event of failure of the rear lamp and so, by this arrangement, there is substantially no waste of electric energy and a lighting

failure is immediately indicated and easily corrected.

It will be appreciated that where lamp bulbs and holders of the screw-in type are used, the connecting wire 24 is dispensed with and the socket of the lamp holder makes the necessary connection between the one pole of the lamp bulb and the base piece 4.

10 I claim:

An electric lighting apparatus of the specified kind, comprising an insulating base having an insulating projection, a lamp holder containing a spare rear light bulb and mounted on the said projection, a coil wound on a bobbin and attached to the said base, a core in the said bobbin, an armature mounted on a spring arranged in direct electric contact with the exterior of the lamp

holder, a bracket mounted on the base and 20 carrying a contact screw against which the armature bears under the action of the said spring, and four terminals provided on the said base; one of which is electrically connected to one end of the coil, a second of which is electrically connected to the other end of the said coil and to one contact of the lamp holder, a third of which is electrically connected to the said bracket and to the fourth terminal, the second contact 30 of the lamp holder being electrically connected to or forming a part of the exterior of the lamp holder.

In testimony whereof, I have signed my name to this specification at Manchester in 35 the county of Lancaster, England, this 31st day of August 1926.

HARRY CUMPSTY PROCTER.
